UNITED STATES PATENT OFFICE.

CARL E. CHRISTOPHEL, OF PEARL RIVER, NEW YORK, ASSIGNOR TO DEXTER FOLDER COMPANY, OF PEARL RIVER, NEW YORK, A CORPORATION OF NEW YORK.

SHEET-FEEDING MACHINE.

1,357,612.

Specification of Letters Patent.

Patented Nov. 2, 1920.

Original application filed October 9, 1918, Serial No. 257,517. Divided and this application filed February 26, 1919. Serial No. 279,353.

To all whom it may concern:

Be it known that I, CARL E. CHRISTOPHEL, a citizen of Germany, residing at Pearl River, county of Rockland, State of New York, have invented certain new and useful Improvements in Sheet-Feeding Machines, of which the following is a specification.

This invention was originally embodied in my copending application Serial No. 257,517, filed October 9, 1918, and therefore constitutes a division of said application. It relates to that class of sheet-feeding machines in which the upward feed of a pile-carrying table is subjected to the control of certain instrumentalities which become operative when the height of the pile becomes reduced below a certain minimum limit and which operate to terminate the action of said table feed as soon as the top of the pile has been raised to a certain maximum limit. The primary object of this invention is to provide improved pile raising means, which becomes operative upon a new pile of sheets as soon as a preceding pile has become exhausted. To accomplish this object, my invention contemplates a reversible feed drive shaft in connection with chains or the like which may be secured at opposite ends to different pile-supporting tables so that as soon as the pile is exhausted from one table, the table-feeding mechanism may at once become actively operative upon the other table merely by reversing the pile feeding operation. Other objects of invention will appear in the specification and be pointed out in the claims, reference being had to the accompanying drawings which show my invention in a preferred embodiment. In the drawings,

Figure 1 is a plan view of a sheet feeding machine embodying my invention, parts being omitted for the sake of clearness,

Fig. 2 is a side elevation of the same,

Fig. 3 is a rear diagram of the operating connections for imparting a pile elevating movement,

Fig. 4 is a diagrammatic side elevation of the main clutch mechanism,

Fig. 5 is a top plan view of the same,

Fig. 6 is a side elevation on an enlarged scale of the pile elevating ratchet feed mechanism.

In the embodiment of my invention shown on the drawings, base sockets 1 may be secured to the floor by any suitable means and

serve to mount the uprights or standards 2 which are rigidly connected at the top by the top rails 3. Rigid with the top rails 3 are suitable brackets or bearings for journaling the shafts 4 which extend on horizontal axes along opposite sides of the machine. Keyed to the shafts 4 are sprockets 5 over which run the double-ended chains 6. Chains 6 are arranged in pairs on opposite sides of the machine and each end of each chain is provided with a clevis 7 which is detachably secured to a collar 8 which turns freely on the rods 9. Each of the rods 9 is provided with a disk 10 provided with sockets 11 which are adapted to receive a pin or lever for oscillating the rod 9, said rod being provided with grooved portions 12 which mesh into similarly grooved undersurfaces of the I-beams 13. The outer ends of the rods 9 are provided with bifurcated 70 sockets 14 which slidably engage the standards 2, at least one of said sockets 14 being movable endwise on the bar 9 to permit it to be taken from the machine when desired. The I-beams 13 are adapted to support the 75 paper table 15 which, before it is lifted by the I-beams 13, may rest upon suitable rollers 16 journaled in standards 17 which rest in sockets in foot supports 18, said foot supports being pivotally connected at 19 to the 80 base sockets 1. It will be seen from this description that the chains 6 may be moved in either direction, so that when a paper table 15 has been elevated almost to the upper 85 limit of its movement, another paper table 90 may be attached to the lower end in readiness to receive another pile of sheets which in its turn will be fed upwardly by reversing the direction of rotation of the shafts 4. Adjacent to the sprockets 5 on the forward 95 ends of the shafts 4 are keyed worm wheels 20 which mesh with worms on a transverse shaft 21 provided with a suitable socket 22 for the reception of a crank (not shown). Keyed to this shaft is a gear 23. Co-operating with the gear 23 as shown best in Fig. 3 is a planetary system, comprising a rotary plate or disk 24 provided with radial sockets 25, 26, 27 and 28 which are adapted to receive the end of a threaded bolt 29 which 100 is mounted in a threaded socket 30 secured to the frame of the machine. The bolt 29 is provided with a hand grip 31. Rotatably mounted upon the plate or disk 24 is a gear 32 which is journaled on a stud 198 and 110

meshes with the gear 23 and an idler 33 which, according to the positions shown in Fig. 3, is interposed between the gear 32 and a gear 34 which is keyed to a stub shaft 5 35. Also keyed to the shaft 35 is a ratchet 36 which is adapted to be moved by a pawl 37 which is pivotally mounted on a pin 38 carried by an oscillatory block 39. A spring rod 40 reciprocates in a post 41 and carries 10 a compression spring 42 which is interposed between the post 41 and a collar 43 which is secured to the rod 40. A pin 44 serves to pivotally connect the block 39 to one end of a slotted link 45, and is provided at its 15 other end with a slot 46 within which reciprocates a crank pin 47 carried by the rotary disk 48. As shown in Fig. 5, the disk 48, which rotates about the axis of shaft 49 is rigidly connected to a gear 50 20 which is meshed with a gear 51 keyed to the stub shaft 52. Also keyed to the stub shaft 52 is a bevel gear 53 which meshes with a bevel pinion 54 keyed to the drive shaft 55. The shaft 49 is the cam shaft or main drive 25 shaft of the feeding machine, the gear 50 and disk 48 being freely journaled thereon. Keyed to the cam shaft 49 is a disk 56 which is provided with a clutch pin 57, said clutch pin being normally engaged by a clutch 30 lever 58 which is pivoted at 59 on a pin carried by the gear 50. Said clutch lever is provided with a spring arm 60 to which is pivotally connected a spring rod 61 upon which is mounted a spring 62 tending to 35 hold the clutch lever 58 and pin 57 in engagement. A segmental cam 63 is reciprocable axially of the cam shaft 49 and over the peripheral surface of the disk 56. Said cam 63 is provided with pins 64 which are 40 reciprocably mounted in the bracket 65, one of said pins being extended inwardly and provided with an inclined groove 66 which co-operates with a cam plate 67 carried by a cam arm 68 which is keyed to a transverse 45 shaft 69 which may be operated at will, or by the caliper mechanism to throw the segmental cam 63 into and out of position to intercept the cam roller 70 which is journaled on a pin 71 carried by the cam lever 50 58. Whenever the cam roller 70 is forced to travel over the segmental cam 63, the clutch lever 58 is left out of engagement with the clutch pin 57 and the cam shaft 49 is disconnected from the driving train. As 55 shown in Fig. 6, the shaft 35 has keyed thereto a dog 72 with which co-operates a lever arm 73, which swings freely about a pin 74 which projects laterally from the bracket 65. As long as the arm 73 locks the dog 60 72, the oscillatory block 39 is prevented from being forced in a clockwise direction to bring the pawl 37 into engagement with the next tooth toward the right, which would cause the ratchet 36 to be moved one tooth during 65 the next displacement of the slotted link 45.

The pile holding table is thus held at a fixed elevation until such time as the arm 73 is moved out of engagement with the dog 72 to permit the movement just referred to. For this purpose, an arm 75 which is keyed to a rock shaft 76 is adapted to be moved into engagement with the lever arm 73 at a moment when the cranking pin 47 has reached the left end of its travel and thus served to remove the tension of spring 75 42 from the lever arm 73. The rocking movement of the shaft 76 corresponds with the vertical movement of the forwarding mechanism shown and described in my above identified copending application, Serial No. 80 257,517 according to which the lever arm 75 operates the lever arm 73 whenever the sheet feeding suckers are obliged to drop more than a predetermined distance to secure their hold upon the top sheet of the 85 pile. Thereupon the lever 73 is displaced and the succeeding reciprocatory movements of the link 45 causes the pile to be raised step by step until such time as the following movements of the sheet forwarders is 90 limited sufficiently to prevent the arm 75 from engaging the lever 73.

Referring now to Figs. 1, 2 and 3, the armature gear 162 of the motor 163 meshes with the larger gear 192 of a compound of 95 which the smaller 193 meshes with a gear 194 on a shaft 195. Keyed to the shaft 195 is a gear 196 which meshes with an idler 197, said idler being adapted to mesh with gear 32 (see Fig. 3) for driving shaft 21 100 in one direction or to mesh with idler 33 for driving said shaft in the opposite direction.

The parts being in the position shown in Fig. 2 according to which the pile on the 105 upper table is supposed to be exhausted, it now becomes necessary in putting the second pile into action, to raise the lower set of bars 9 until the I-beams 13 lift the paper table 15 from the rollers 16. For this purpose, the motor 163 is preferably used, since it operates more rapidly than the regular table-elevating mechanism to bring the parts into starting position. Depending upon which direction the chains 6-6 are 110 to be fed, the planetary system is adjusted by releasing the bolt 29 from its socket 28 in the disk 24, after which a handle 198 carried by the disk 24 is employed to revolve the planetary system until either the 115 gear 32 or gear 33 is brought into mesh with the gear 197. If it is necessary to bring the gear 32 into mesh for driving in one direction, the planetary system is revolved until the bolt 29 is permitted to enter 120 the socket 25. In this event the pitch circle of gear 32 is brought into tangency with that of gear 197. In this connection it is to be noted that the pitch diameter of gear 32 is just sufficient to fill the gap between 125 130

the pitch circles of gears 23 and 197, said gear 32 being suitably disposed on the disk 21 for this purpose. Furthermore, the intermeshing gears 32 and 33 protrude the same 5 distance from the axis of revolution of the disk 24 so that when the gear 33 is to be put into mesh with gear 197 for driving in the opposite direction, the planetary system is revolved until the socket 26 is opposite 10 the bolt 29. The bolt 29 having been forced home, gear 197 transmits power through gears 33, 32 and 23 to shaft 21, the I-beams 13 being rapidly raised until they lift the paper table 15 from the rollers 16 after 15 which the bolt 29 is withdrawn and the planetary system moved to the position shown in Fig. 3, in which the table-lifting mechanism is operated automatically depending on the condition of the pile with 20 reference to the forwarding suckers. Whenever it becomes necessary to reverse the step by step feed from that provided in the arrangement of parts shown in Fig. 3 a counter clockwise revolution of the disk 24 25 brings the gear 32 into mesh with gear 34 which is rotated step by step by ratchet 36 depending upon the height of the paper pile.

I claim:

1. In a machine of the character described, uprights or standards, paper-carrying tables, means slidably engaging said uprights or standards for movably supporting said tables, and means movable in either of two opposite directions for imparting vertical movement to said tables, said table-supporting means including rods provided with sockets for slidably engaging said uprights or standards, said rods being movable into and out of operative position.
2. In a machine of the character described, uprights or standards, vertically movable rods slidably engaging said uprights or standards, power driven shafts arranged substantially in the planes of movements of said rods, flexible means operated by each of said shafts and having opposite ends thereof connected to different rods, and means for rotating said shafts in opposite directions.
3. In a machine of the character described, uprights or standards, vertically movable rods slidably engaging said uprights or standards, power driven shafts arranged substantially in the planes of movements of said rods, flexible means operated by each of said shafts and having opposite ends thereof connected to different rods, and means for rotating said shafts in opposite directions, said means including a motor, a shaft geared to each of the first-mentioned shafts, and a planetary system interposed between said motor and the second-mentioned shaft.
4. In a machine of the character described, uprights or standards, vertically

movable rods slidably engaging said uprights or standards, power-driven shafts arranged substantially in the planes of movements of said rods, flexible means operated by each of said shafts and having opposite ends thereof connected to different rods, and means for rotating said shafts in opposite directions, said rotating means including a power transmitting shaft, a disk oscillatable upon said shaft, a gear keyed to 70 said shaft, a pair of meshing gears journaled on said disk, one of the last-mentioned gears being in mesh with said gear keyed to the shaft, and a gear driven by said motor and into mesh with which either 75 of said meshing gears may be moved by the oscillation of said disk.

5. In a machine of the character described, a power driven shaft, flexible means operable by said shaft in either 80 of two directions, said flexible means being adapted to be connected at either end to a pile supporting table, and means for rotating said shaft in either direction said rotating means including another shaft 85 connected to the first-mentioned shaft, a gear keyed thereto, a power driven gear, and a pair of intermeshing gears revoluble about the axis of the second-mentioned shaft to connect said power driven gear to 90 the gear on the second-mentioned shaft through one of said intermeshing gears or through both in train.

6. In a sheet feeding machine, uprights or standards, oppositely arranged rods 100 slidably engaging said uprights or standards, a pile-supporting table carried by said rods, sheet feeding means adapted to feed sheets from the top of said pile, rotary shafts arranged above said rods respectively, flexible members movable by each of said shafts one end of each of said flexible members being detachably connected to one of said rods, other rods slidably engaging said uprights or standards and connected to the other end of said flexible members, another paper table carried by said other rods, and means for rotating said shafts in opposite directions.

7. In a sheet feeding machine, uprights 115 or standards, oppositely arranged rods slidably engaging said uprights or standards, a pile-supporting table carried by said rods, sheet feeding means adapted to feed sheets from the top of said pile, rotary 120 shafts arranged above said rods respectively, flexible members movable by each of said shafts one end of each of said flexible members being detachably connected to one of said rods, other rods slidably engaging said uprights or standards and connected to the other end of said flexible members, another paper table carried by said other rods, and means for rotating said shafts in opposite directions, said means in- 125 130

- cluding a gear for driving said shaft, a pinion in mesh with said gear and revoluble about the axis of said gear, an idler meshing with said pinion independently of said 5 gear and a power driven gear suitably disposed to have either said pinion or said idler brought into mesh by the revolution of said pinion and idler about the axis of the first-mentioned gear.
10. 8. The combination with sheet feeding means, of a plurality of pile supporting tables for moving successive piles of sheets to be operated upon by said feeding means, means adapted to be connected to both of 15 said tables, said means being adapted when moved in one direction to move one of said tables and when moved in another direction to move the other of said tables, and means depending upon the height of the pile on 20 one of said tables for operating said table moving means.
9. The combination with sheet feeding means, of a plurality of pile supporting tables for moving successive piles of sheets 25 to be operated upon by said feeding means, means adapted to be connected to both of said tables, said means being adapted when moved in one direction to move one of said tables and when moved in another direction 30 to move the other of said tables, and means depending upon the height of the pile on one of said tables for operating said table moving means, said pile controlled means being reversible to successively move said 35 tables.
10. The combination with sheet feeding means, of a plurality of pile supporting tables for moving successive piles of sheets to be operated upon by said feeding means, 40 means adapted to be connected to both of said tables, said means being adapted when moved in one direction to move one of said tables and when moved in another direction to move the other of said tables, and means 45 depending upon the height of the pile on one of said tables for operating said table moving means, said pile controlled means including a gear operated by said machine depending on the height of one of said piles, 50 a gear for driving said table moving means, a pinion in mesh with the last-mentioned gear, and an idler in mesh with said pinion independently of the last-mentioned gear,

said idler and pinion being revoluble about the axis of the last-mentioned gear to bring 55 either said idler or said pinion into mesh with the first-mentioned gear.

11. In a machine of the character described, a vertically movable pile holding table, sheet feeding means operating upon the top of a pile of sheets carried by said table, a gear driven by said machine depending upon the height of a pile of sheets on said table, a gear for raising or lowering said table, a pinion in mesh with said gear, 65 and an idler in mesh with said pinion, said pinion and idler being revoluble about the axis of the last-mentioned gear to bring the said pinion or said idler into mesh with the first-mentioned gear to move said feed table 70 either upwardly or downwardly.

12. In a machine of the character described, a pile supporting table, sheet feeding means operating on the top of said pile, means for moving said table upwardly or 75 downwardly, a step by step feeding mechanism under the control of said sheet feeding mechanism, a continuously movable feeding mechanism, and reversible means movable alternatively into and out of operating connection with said step by step feeding mechanism or said continuously movable feeding mechanism.

13. In a machine of the character described, a pile carrying table movable upwardly or downwardly, a shaft rotatable in opposite directions to transmit an upward or downward movement to said table, a gear keyed to said shaft a sheet feeding mechanism adapted to operate upon the top of a 90 pile of sheets carried by said table, two other gears spaced from each other and from the first-mentioned gear, means for imparting continuous rotation to one of said gears, means depending on the height 95 of a pile of sheets on said feed table for imparting a step by step rotation to the other of said other gears, a pinion in mesh with the first-mentioned gear, an idler in mesh with said pinion, said pinion and idler being revoluble about the axis of the first-mentioned gear, to bring either said pinion or said idler into mesh with either of said other gears.

CARL E. CHRISTOPHEL.
